FIG. 3.

UNITED STATES PATENT OFFICE.

LAWRENCE S. SCHMIDT, OF PITTSBURGH, PENNSYLVANIA.

MEANS FOR HEATING BOILERS BY WASTE GASES.

1,276,421.

Specification of Letters Patent. Patented Aug. 20, 1918.

Application filed February 4, 1916. Serial No. 76,119.

To all whom it may concern:

Be it known that I, LAWRENCE S. SCHMIDT, a citizen of the United States, residing at Pittsburgh, in the county of Allegheny and State of Pennsylvania, have invented certain new and useful Improvements in Means for Heating Boilers by Waste Gases, of which the following is a specification.

My invention relates to means for heating 10 boilers by the waste gases of open hearth and other regenerative furnaces, being particularly designed to provide for maximum efficiency of said gases when utilized for heating waste heat boilers.

15 The utilization of the waste heat from regenerative furnaces for heating boilers has heretofore been practised, but the means employed have been of such a character that they have not proven satisfactory due to 20 heat losses and operating conditions present in the structures employed.

Heretofore, the waste gases have been passed to the waste heat boiler by means of a flue or passage directly connected with the 25 stack or with the stack flue, valves in said passages being employed to control the passage of the waste gases, permitting the gas to be passed to the boiler or to the stack, as desired.

30 Waste gases from the open hearth and the checker chambers carry considerable dust and where these gases are employed for heating boilers, the dust is deposited on the boilers, thus requiring frequent cleaning. With 35 the present structures this cleaning has been performed under great difficulties, due primarily to the leakage of gas past the valve in the flue or passage leading to the boiler. Another objectionable feature also due to 40 valve leakage is the admission of air to the waste gases on their way to the boiler to be heated.

To overcome the above stated troubles now 45 present in structures to which this invention relates and to pass the gases from the regenerative furnace to the boiler with a minimum heat loss are among the objects of the present invention.

In accomplishing these objects, I employ

a construction in which a rearrangement 50 of the connections between the furnace, boiler and stack is provided, eliminating the direct connections heretofore employed and employing a new and improved valve structure and port sealing means of a character 55 that will not lower the temperature of the gases in passing to the boiler.

In the accompanying drawings, in which similar reference characters indicate similar parts in each of the views,

60 Figure 1 is a diagrammatic view showing one way in which the conduits may be arranged to efficiently carry out the purposes of the present invention.

Fig. 2 is a side elevation of a preferred 65 form of valve, the view showing more particularly the mechanism for providing the shifting operations.

Fig. 3 is a vertical sectional view taken on the line 3—3 of Fig. 5, the view also showing 70 portions of the conduits.

Figs. 4 and 5 are sectional views taken on the lines 4—4 and 5—5 respectively of Fig. 3.

Referring more particularly to Fig. 1, 10 and 10^a indicate air ports of the regenerative 75 or open hearth furnace structure; 11 and 11^a represent the gas intake ports, and 12 and 12^a the gas ports. 13 indicates a conduit or flue which, under prior practice, generally leads direct to the stack, indicated at 14. 80 This flue is brought into proper connection with the ports 10 or 10^a and ports 12 or 12^a through the use of a suitable valve mechanism which may be of the type presently described, although other forms may be employed. 85

Instead, however, of leading the transfer flue 13 direct to the stack, flue 13 terminates in a vertically extending port 13^a arranged between two vertically extending ports 14^a 90 and 15^a, port 14^a being one entrance to a conduit 14^b leading to the stack, the arrangement being such that when port 13^a is connected to port 14^a, the gases from the furnace, after reaching conduit 13 from the respective conduits, will pass direct to the stack. If, however, port 13^a is connected to port 15^a, these gases will pass from conduit 95

13 into conduit 15 leading to the boiler 16, the latter having an off-take 17 which leads to the stack. I prefer to employ an ex-
hauster 18 at the outlet side of the boiler in
order that the draft of the stack may be
augmented.

This arrangement necessitates connection
of port 13^a with either of ports 14^a or 15^a,
depending upon whether the outgoing gases
from the furnace are to be utilized in heat-
ing the boiler. By providing the break in
continuity of the conduits, leakage of gases
in the undesired path is prevented, so that
when it is desired to clean the boiler, break-
ing of the connections between ports 13^a and
15^a prevents any liability of the gases enter-
ing the boiler while the workmen are present
therein, the gases then being delivered to the
stack, the boiler being by-passed. The stack,
during this operation, is entirely discon-
nected from the boiler passage, and no air
therefrom is drawn into the waste gases. To
permit of placing the boiler into or out of
the path of the gases at will, I employ a re-
versing valve structure, and to reduce heat
losses at this point as far as possible, I pref-
erably provide a reversing valve of the type
indicated in the drawings, this arrangement
operating to seal the connections, and at the
same time materially reduce, if not entirely
eliminate, the presence of an exposed water
surface in the travel path of the gases.

As shown more particularly in Figs. 3 and
5, ports 13^a, 14^a and 15^a are formed with an-
nular portions projecting above the normal
plane of these conduits, these ports being
preferably circular in contour, although this
is not absolutely essential, it being clear that
this contour may be varied in any desired
manner.

Surrounding each of these annular por-
tions of the port is a trough 19 adapted to
carry the water for the water seal, these
troughs being comparatively narrow in
cross sectional width and having sufficient
depth to provide for proper sealing action.

Coöperating with these ports is a revers-
ing valve 20. This valve has a cross sec-
tional contour corresponding to the contour
of troughs 19, the drawing showing this
cross sectional contour as circular. The
travel path of the gases through the valve
is also shown as being on the arc of a circle,
thereby eliminating as far as possible the di-
rect impinging action of the gases which
occurs where the valves are shallow.

In the drawing, the valve is shown tubu-
lar and preferably formed metallic with a
lining 20^a of refractory material, the ends
of the metallic portion projecting beyond
the ends of the lining, these projecting por-
tions 21 forming the parts which enter the
troughs 19 to complete the seal. As shown,
I also preferably provide an angle 22 at the

ends of the lining, these angles being con-
nected to the metallic tube in suitable
manner, serving not only to protect and po-
sition the ends of the lining but also form-
ing members which may contact with the
inner seal of the trough and coact with the
trough to support the valve, but in addi-
tion, act to segregate the seal from the
gases, thus placing the seal entirely out
of direct contact with the gases.

As will be obvious, the use of narrow 75
troughs and the projecting portions 21 ne-
cessitates practically a uniform vertical
travel of the valve before its lateral shift-
ing movement can take place, since the pro-
jecting portions 21 must be entirely above 80
the plane of the troughs before the lateral
motion takes place. To provide for this
action, I employ certain operating mecha-
nisms which first act to raise the valve
bodily, then shift it in the proper direc-
tion without materially increasing the ver-
tical travel after the seal has been broken,
and then permitting the valve to move
downwardly to its new position by the action
of gravity without, however, any material 90
jar effect, these mechanisms automatically
providing this shifting action and at the
same time acting as locking means against
accidental shifting of the valve when in
either of its positions. To provide this 95
action, I employ the following mechanisms:

23 indicates a cam structure in the form
of a plate member, one of these members
being located on each of the opposite sides
of the valve. As shown in Figs. 2 and 3, 100
each member 23 is depressed substantially
midway of its length as at 23^a, the member
on opposite sides of this depression forming
cams 24 which have the cam faces similar in
both cams. The vertical walls of depression 105
23^a are shown as inclined from the vertical
to a small degree, increasing the distance
between the walls at the top of the depres-
sion, so that a member traveling over the
face provided by either of these walls will 110
tend to shift the valve slightly in the direc-
tion in which it is to move, this action con-
tinuing until the top face of the same is
reached, said top face then permitting the
valve to travel in the direction it is to go 115
with freedom, until the opposite end of the
top face of the cam is reached, whereupon,
the cam permits a free dropping action of
the valve. Obviously, these walls may be
made truly vertical.

The valve carries a plurality of rollers 25
properly positioned, which rollers are adapt-
ed to coact with these cam faces, and since
the cam faces are duplicates, it will be under-
stood that the projecting portions 21 will 125
not vary relative to each other and to a plane
intersecting the axes of these portions, al-
though the cam action shifts such plane.

- Consequently, the projecting portions are maintained in proper position to enter the seals provided by the troughs whenever shifting of the valve carries it to a position 5 where the vertical walls of the cams permit the valve to seat, the rollers 25 passing downward during this action.
- 26 and 26^a indicate a pair of shafts which extend from one side of the valve to the other, each shaft being adapted to carry a pair of arms 27 having slot 27^a, these slots being adapted to receive rollers 28 mounted on shaft 29, said latter shaft also carrying rollers 25. Shafts 26 and 26^a are provided 10 with a worm gear 30, each gear being adapted to coöperate with a worm 31 carried by a shaft 32, the latter being driven from a suitable power source, such, for instance, as a motor, the power means being so arranged as to permit shaft 32 to be rotated in either direction. Obviously, rotation of shaft 32 will act to move shafts 26 and 26^a on their axes, the movements of the shaft carrying arms 27, and since shafts 29 extend 15 into the slots 27^a, such movements of arms 27 will provide movements to shaft 29 in the corresponding direction, but since shaft 29 is located within an elongated slot, movements of shaft 29 will not be on an arc having shafts 26 or 26^a as a center, but will, 20 on the contrary, travel in paths which are controlled by cams 24, shaft 29 simply moving within the slot 27^a as may be necessary in following the cam.
- 25 As will be readily understood from Figs. 2 and 3, in which the valve is shown as connecting ports 13^a and 15^a, operation of shaft 32 in a direction to move arms 27 counter-clockwise would first cause rollers 25 to 30 travel up the vertical faces at the right of each cam 24 until these rollers reached the point of juncture of the vertical and horizontal faces of the cam, whereupon, the upper faces of the cams will form the support 35 for the valve, arms 27 simply causing the valve to travel on its support, thus relieving these arms of the support of the valve which was placed on them during the initial vertical travel. The counter-clockwise 40 travel of arms 27 causes the valve to travel toward the left of these figures, until rollers 25 reach the opposite end of the upper portion of cams 24, whereupon, the arms 27 again take up the support of the valve, continuation of these arms gradually lowering 45 the valve into position, it being readily understood that when this lowering action is to take place, the arms are at such an angle to the vertical that free downward movement of the valve is prevented, the downward travel being dependent upon the speed 50 at which the arms 27 travel. Consequently, the valve seats with a gentle motion and since one of rollers 25 passes into de-
- pression 23^a whenever final downward movement of the valve takes place, the valve will be held from any material uncontrolled shifting by reason of the limited amount of play provided by the vertical walls of depression 23^a. Consequently, there is no necessity for the employment of troughs of considerable width, the walls of the depression 23^a acting to prevent shifting of the valve sufficient to prevent entrance of projections 21 into the relatively narrow seal. 55
- Since the initial and final travel of the valve is substantially vertical, thereby causing the projections 21 to leave or enter the seals without material lateral motion therein, it will be readily understood that movements of the valve can be had with considerable rapidity, such initial and final movements being such as to not tend to materially disturb the water of the seal even when the withdrawing or entering movement is rapid. As lateral movement of the valve only takes place after the projections leave the seal, rapid travel in the lateral direction has no effect upon the seal. Consequently, the power device can operate 60 with rapidity and at uniform speed, there being no requirement of any change speed action during the shifting operation. 65
- As will be obvious, the worm and worm gear connection acts as a lock to prevent shifting of the arms 27 except when shaft 32 is operated, so that the position of the valve will be maintained. 70
- It is to be understood that the operating structure, with the exception of the worm and gear connections and shaft 32, are duplicated on the opposite side of the valve. 75
- While the top cam surfaces of cams 24 might be in a single plane, I prefer to make these surfaces in two or more planes, the drawings showing two planes, each slightly inclined to the horizontal with the high portion substantially midway of the length of the cam, thus tending to gradually raise the valve during its lateral travel and insure 80 free movement without, however, carrying the valve to any great extent above the top plane of the ports. As will be readily understood, the downward inclination of the cam during the latter half of its movement 85 would be assisted by the weight of the valve, thus insuring against liability of any sticking action between the arms and the valve; inasmuch as this movement, however, is dependent on the rate of travel of the arm, 90 it will be readily understood that the weight can not so affect the movement as to cause travel of the valve in a manner to damage the structure. 95
- Since the valve acts in connection with 100 but two of the three ports when in its lower normal position, I provide means for closing the remaining port at this time, this 105

means being in the form of a hingedly supported cover 33 carried at each end of the valve, the latter having a supporting structure indicated at 34, to which a member 35 secured to the top of cover 33 is pivoted, cover 33 having a downwardly extending flange, said flange conforming to the contour of the trough and being adapted to provide the sealed condition of the port when the latter is not protected by the valve. As will be seen from Fig. 3, the downward movements of the cover is limited by a suitable stop 34^a which may be in the form of a flange located in the path of travel of member 35, thus limiting the downward movement on such pivot. As this structure is carried by the valve itself, it will be readily understood that the initial vertical movements of the valve acts to raise the cover out of its sealed condition, thereby permitting the valve to continue its movements without liability of the cover preventing such movement.

As there are but three ports to be controlled at this particular point, and two of these ports are controlled by the valve, it will be readily understood that one of the covers 33 need perform no duty, and can therefore be raised. Various means for placing the cover in raised position or providing its movements may be employed, a simple structure being indicated in Fig. 3 in which a cable 36 has its upper end supported at a suitable point, as at 37, and its lower end secured to the cover, each cover having its independent cable. As shown in Fig. 3, the cover at the left is in its port-closing position; however, the cover at the right is shown as raised, this being due to the fact that the point 37 is so positioned relative to the normal positions of the valves, that the length of cable between such point and the cover will not permit the cover to follow the entire movements of the valve when shifting from one position to the other without the cover being moved on its pivot.

It should be understood that this mechanism may also be employed in connection with the other ports referred to, the employment of the valve disclosed herein decreasing the loss of heat units which occurs in connection with the other types. However, the application is not limited to a valve such as disclosed herein at these other ports, since it may be desired to reduce the temperature of the outgoing gas during a passage to conduit 13. It is, however, preferred to employ the type of valve disclosed herein as the connector between conduits 13 and 15 in order that a minimum reduction might be had at this point.

What I claim is:—

1. In apparatus for utilizing waste gases in the heating of boilers and in combination, a boiler, a stack, a waste gas conduit having

a port, a stack flue having a port, a boiler flue having a port, all of said ports arranged in the same horizontal plane and having their axes approximately parallel, and a reversing valve mounted above said ports for connecting the waste gas conduit with the boiler flue port or the stack flue port at will, the movement of said valve to establish connection with one of said ports acting to produce a total break in the continuity of the connections to the other port. 75

2. In apparatus for utilizing waste gases in the heating of boilers and in combination, a boiler, a stack, a waste gas conduit having a port, a boiler flue having a port, said ports of the stack and boiler flues arranged apart from the waste gas conduit port and from each other and without permanent connection therebetween, and a reversing valve mounted above said ports for connecting the waste gas conduit with the boiler flue or the stack flue at will, the movement of said valve to establish connection with one of said ports acting to produce a total break in the continuity of the connections to the other port. 80

3. In apparatus for utilizing waste gases in the heating of boilers and in combination, a conduit forming the waste gas supply, a stack conduit, a boiler conduit, all of said conduits arranged apart and without permanent connections, the axis of the waste gas conduit outlet and the axes of the entrance to the conduits for the stack and the boiler being approximately parallel, and means for connecting said waste gas supply with the boiler or stack at will, the movement of said means to establish connection with one of said ports acting to produce a total break in the continuity of the connections to the other port, said means including an element for closing a port while the break continues. 95

4. In apparatus of the character described and in combination, a pair of ports and a port adapted to be connected to either of said pair of ports, said ports having their axes substantially parallel and arranged in the same horizontal plane, and a reversing valve structure mounted above said ports and shiftable at will, the movement of said valve to establish connection with one port of the pair 115 acting to produce a total break in the continuity of the connections to the other port, said structure including an element for closing such other port while such break continues, said valve being water sealed with the water seals arranged out of the path of travel of the waste gases. 120

5. In apparatus for utilizing waste gases in the heating of boilers and in combination, a boiler, a stack, a waste gas conduit having a port, a stack flue having a port, a boiler flue having a port, all of said ports arranged in the same horizontal plane and having 125

their axes approximately parallel, and a reversing valve structure mounted above said ports for connecting the waste gas conduit with the boiler flue port or the stack flue port at will, the movement of said structure to establish connection with one of said ports acting to produce a total break in the continuity of the connections to the other port, said structure including an element for closing such other port while such break con-

tinues, said element being rendered active and inactive by the movements of the structure.

In testimony whereof I affix my signature in presence of two witnesses.
